UNITED STATES PATENT OFFICE

MAXIMILLIAN WILLIAM WUESTHOFF, OF SAN FRANCISCO, CALIFORNIA.

HINGE FOR TOILET SEATS.

Application filed October 3, 1923. Serial No. 666,368.

To all whom it may concern:

Be it known that I, MAXIMILLIAN WILLIAM WUESTHOFF, a citizen of the United States, residing at the city and county of San Francisco and State of California, have invented new and useful Improvements in Hinges for Toilet Seats, of which the following is a specification.

This invention relates to hinges for toilet seats and covers.

It is the object of the invention to improve hinges of the character referred to, whereby to provide a simple, inexpensive hinge by which a toilet seat and its cover may be hinged to a toilet bowl, said hinge being neat in appearance and capable of being easily cleaned. A further advantage is to leave exposed as few metallic parts as possible.

Prior seat hinges ordinarily include a pair of standards carrying a hinge pin to which both the seat and its cover are connected by brackets or arms. Not only are the standards exposed to dust and dirt, but likewise the hinge pin and two pairs of arms and brackets which connect the seat and cover to the pin. While easily catching dust and dirt, these exposed parts are not so readily accessible for cleaning. In time they become unsightly. Attempts have been made to overcome these objections by extending the hinge pin directly through the material of which the seat is formed and providing a second hinge pin for the cover in a raised bearing or lug formed upon the seat. While this avoids the necessity for brackets and conceals the hinge pins, it requires two different hinges, and as a result thereof, if the cover be opened when the seat is being raised or lowered, the cover will ride up or down against the wall or woodwork at the back of the toilet.

In the present invention I provide a pair of standards on which is carried a hinge pin, the latter passing through the material of the seat cover and concealed thereby. A yoke-like strap depends from the hinge pin and the seat itself is directly secured to this yoke. Thus there is but one hinge pin, and it is entirely concealed. The yoke-like dependent straps are scarcely visible, and afford no chance for dust or dirt to collect. The only exposed parts are the two standards, which are easily accessible for cleaning.

One form which the invention may assume is exemplified in the following descrip-

tion and illustrated in the accompanying drawings, in which:

Fig. 1 is a fragmentary view in plan disclosing a toilet seat and its cover hinged to a toilet bowl by means of a hinge embodying the preferred form of the present invention.

Fig. 2 is a fragmentary view in perspective of the hinge, disclosing the manner in which the toilet seat and its cover are connected thereto.

Fig. 3 is a fragmentary side elevation of a toilet bowl with my improved hinge mounted thereon.

Referring more particularly to the accompanying drawings, 10 indicates a toilet bowl. As in certain standard designs, the bowl is formed with a flat portion 11 which projects rearwardly from the rim of the bowl. The portion 11 serves as mounting for a pair of hinge standards 12, each of which is formed with a flange 14 which bears upon the portion 11. Studs 15 are formed as continuations of the standards and project through the portion 11 of the bowl. These studs are fitted with washers and nuts for clamping the standards in place as clearly shown in Fig. 3.

A hinge pin 17 extends between the upper ends of the standards 12 and serves to support a bail-shaped hinge plate 18. This hinge plate comprises a flat metal member 19, the ends of which are upturned to form arms 20^a which are pivoted on the hinge pin 17. The toilet seat 20 is formed with an extension 21 which fits tightly between the arms 20^a on the hinge plate beneath the hinge pin, and is firmly secured to the hinge plate by means of a rivet 22 and screws 22^a.

The toilet seat cover 23 is formed with an extension 24 which fits between the lugs above the seat 20 and is directly pivoted on the hinge pin 17 as clearly shown in Fig. 2.

It is obvious from the drawings that the seat and its cover may be raised independently or in unison.

The seat 20 hinges about the pin 17, as does also the cover, and hence if the cover be in open position when the seat is being raised or lowered, it will not be moved or disturbed, as is the case where the hinge for the cover is mounted upon the rear end of the seat. It will be noted that the only parts of this hinge which are open to the collection of dust or dirt are the standards 12, and these are readily accessible for cleaning. The pin 17 is wholly concealed in

the material of the cover 23, and the only parts of the hinge plate 18 exposed are the ends of the arms 20^a.

By my invention I have provided a simple hinge for hinging a toilet seat and its cover to a toilet bowl. The hinge is of simple and inexpensive construction, and consists of a minimum of parts, whereby it may be easily cleaned.

10 While I have shown and described the preferred form of the invention, it is understood that various changes may be made in its construction without departing from the invention as defined in the appended claims.

15 Having thus described my invention, what I claim and desire to secure by Letters Patent is:—

1. A hinge for connecting a toilet seat and its cover to a toilet bowl comprising a pair of standards, a hinge pin extending between the upper ends of said standards, hangers pivoted to said pin and dependent

therefrom and disposed one adjacent each standard, an extension on said cover fitting between said hangers and pivoted on said hinge pin which extends through said extension, and an extension on said seat fitting between said hangers beneath said hinge pin and being rigidly secured to said hangers.

2. A hinge for connecting a toilet seat and its cover to a toilet bowl said hinge comprising a pair of upright standards fixed on the bowl, a hinge pin extending between said standards, a bail-shaped hinge plate, the ends of which are pivoted on said pin adjacent said standards, an extension on the seat cover extending between the ends of said plate and pivoted on said hinge pin which extends through said extension, and an extension on said seat fitting between the ends of said plate beneath the cover and rigidly secured to said plate.

MAXIMILLIAN WILLIAM WUESTHOFF.
